WARP PILE FABRIC AND METHOD OF
MAKING SAMEGeorge A. Morgan, Sanford, Maine, assignor to
Sanford Mills, Sanford, Maine, a corporation
of Maine

Application August 15, 1934, Serial No. 739,899

20 Claims. (Cl. 139—402)

This invention relates to warp pile fabrics made on a pile wire loom and the method of making the same and has for its object to provide and produce such a warp pile fabric in which 5 adjacent rows of pile loops of a different character and particularly adjacent rows of cut and uncut pile loops are brought into and stand in such substantial alignment as to produce the effect of a single composite row, in which this 10 effect is produced throughout the entire face of the fabric and in which in all cases there is presented a fast pile, that is, a construction in which each leg of each loop is securely anchored in the ground of the fabric.

- 15 In the patent to Hope, No. 1,817,704, granted October 7, 1919, there is disclosed a warp pile fabric and the method of making the same which has been in extensive and successful use. But in the Hope construction each pile warp end in the 20 fabric alternately runs on top of four or more picks of filling, rendering it impossible to form a pile loop over any of the pile wires where the pile warp end thus runs on top of the four or more picks of filling. As a result, not only is 25 there a large amount of the relatively expensive pile warp embedded in the ground of the fabric but it is impossible to bring this portion of the pile warp to the face in the form of pile and thus make a full, rich pile surface. In the construction of the Hope patent the row of cut loops formed by a pile knife wire next to a row of uncut loops formed by a plain pile wire were 30 brought into substantial alignment so as to have the appearance of being in the same row, but this was secured by having legs of loops in the adjacent rows extend up between the same pair of picks of filling as well as by floating each pile warp end alternately over the top of four or more 35 picks of filling where it is not available as pile.
- 40 In the present invention the desired result of causing adjacent rows of pile loops of a different character such as a row of cut and a row of uncut pile loops to be brought into substantial alignment in the finished fabric so as to produce the 45 appearance of being in the same row is secured. But this is done by a novel principle and in such a manner as to enable a wide variety of pattern effects to be secured and the pile to be distributed throughout the entire face of the fabric giving a full, rich effect while at the same time securing a fast pile or one in which each leg of each loop is securely anchored by being interwoven with the ground of the fabric.

50 In the present invention the fabric is formed with repeats of four picks of filling and a basic

feature of the invention resides in the employment of what is herein termed a free pick. That is, in each form of construction which the invention may take, there are in each repeat two parallel rows of loops of a different character such as a row of cut loops and a row of uncut loops with one pick of filling between these rows over which there is no loop of pile and with no crossing of the ground warp ends which will prevent this pick of filling from sliding into juxtaposition with an adjacent pick of filling. It will be understood that the ground warp ends in a warp pile fabric are woven under a relatively heavy tension while the pile warp ends which are drawn up at intervals to form the pile are woven under a comparatively light tension. Consequently the movement laterally of the free pick unhindered by any crossing of the ground warp ends which are under the heavy tension is only restrained by the relatively light tension of some of the pile warp ends and consequently this free pick in each case when the fabric is beaten up and the pile wire withdrawn is shifted into juxtaposition to the previous adjacent pick of filling and this acts to bring the rows of pile loops formed by adjacent wires into the desired substantial alignment.

Another important feature of the invention is that each pile warp end is thus enabled to form at least one loop, that is, in the preferred form 30 either one cut or one uncut loop, in each repeat of four picks, thus enabling a full, rich pile surface to be secured.

These and other objects and features of the invention will appear more fully from the accompanying description and drawings and will be particularly pointed out in the claims.

The drawings illustrate diagrammatically the relation of the different yarns and pile wires employed in the production of three different 40 forms of the invention.

In the drawings:

Fig. 1 is a perspective view of a preferred form of the invention in which the pile wires and picks of filling are inserted in sequence, in which 45 there is a ground warp end for each pile warp end and in which all of the ground warp ends cross between each repeat of four picks of filling.

Figs. 2, 3, 4, and 5 illustrate in elevation the relation of the groups of yarns and pile wires containing the group of warp ends shown respectively at 2, 3, 4 and 5 in Fig. 1.

Fig. 6 is a perspective view of another form of the invention in which a pile wire and a pick of filling are inserted simultaneously in the weaving 55

operation, in which there are two ground warp ends for each pile warp end, and in which all of the ground warp ends cross between each repeat of four picks of filling.

5 Figs. 7 and 8 illustrate in elevation the relation of the groups of yarns and pile wires containing the group of warp ends shown respectively at 7 and 8 in Fig. 6.

10 Fig. 9 is a perspective view of a third form of the invention in which a pile wire and a pick of filling are inserted simultaneously in the weaving operation, in which there are two ground warp ends for each pile warp end, and in which in each repeat of four picks of filling one set of ground warp ends passes successively over the first and second, under the third and over the fourth pick of filling while the other set passes successively under the first and over the second, third and fourth picks of filling.

15 20 Figs. 10 and 11 illustrate in elevation the relation of the groups of yarns and pile wires containing the group of warp ends shown respectively at 10 and 11 in Fig. 9.

25 In the weaving of a warp pile fabric on a pile wire loom, pile wires are successively inserted transversely parallel with the picks of filling, the pile warp ends are formed into loops over these pile wires, and, as the weaving proceeds, the foremost pile wire is withdrawn and reinserted behind the last pile wire. There is thus formed across the fabric parallel rows of loops, the number and position of the loops in each row depending upon whether the various pile warp ends are raised over the pile wire or held beneath the pile wire 30 35 when it is inserted. These pile wires may be of different heights and they may be either plain pile wires, which result in the formation of closed loops, or they may be provided with a knife at the end which, as the pile wire is withdrawn, acts to form cut pile loops. In any case, all the loops 40 45 which are formed in any given row must be of the same character.

50 In the weaving with pile wires, two methods are commonly employed. In the one method the pile wire is inserted between successive beat-ups of the lay and without any insertion of a pick of filling, while in the other method the pile wire is inserted simultaneously with the insertion of a pick of filling. The present invention is shown as 45 50 adapted to either of these methods.

55 The present invention enables loops constituting one row to be brought into substantial alignment with the loops constituting an adjacent row so that for all practical purposes the appearance is such that the two rows of loops have the appearance of forming a composite row made up of the two different kinds of loops formed in the 60 65 separate rows. This enables a wide variety of pattern effects to be secured.

60 65 In the various constructions illustrated, the rows of loops are shown as formed alternately by knife pile wires and plain pile wires, thus producing alternately a row of cut pile loops and a row of uncut pile loops.

65 70 In the construction shown in Figs. 1 to 5, inclusive, the weaving is proceeding toward the right and a row of cut loops and a row of uncut loops at the left have been completed. The ground warp ends are divided into two sets 12 and 13, the 75 set 12 passing alternately over and under four successive picks of filling and the set 13 passing alternately under and over the same four successive picks of filling so that all of these ground warp ends cross on the same line transversely of the fabric and divide the fabric into repeats of

four picks of filling, a, b, c and d, such repeats being indicated at 14, 15, 16 and 17.

The knife pile wires 18 and the plain pile wires 19 are inserted in alternation, the knife pile wire 18 being inserted between the successive picks of filling a, b and the plain pile wire between the successive picks of filling c, d.

10 The warp pile ends, of which eight are illustrated at 20 to 27, inclusive, alternate with the ground warp ends so that there is one pile warp end to each ground warp end. These pile warp ends under the control of suitable shed-forming mechanism are operated to form loops over the respective pile wires as desired by the pattern to be produced but in the preferred form and to produce the full, rich face, each pile warp end passes over one pile wire in each repeat of four picks of filling and when knife and plain pile wires are employed, the construction readily enables the warp end extending from each leg of a cut pile loop to be 20 25 interwoven under, over, and under successive picks of filling so that the pile is always fast in the ground.

25 It will be observed that the pile warp ends are so interwoven with the picks of filling that there is no row of loops formed over the third pick of filling c in each repeat and as the ground warp ends cross only between the successive repeats, there is no crossing of the ground warp ends between this pick of filling c and the previously 30 inserted pick of filling b. Consequently as the fabric is beaten up, there is nothing except the light tension on the pile warp ends to prevent this free pick of filling c from being shifted into juxtaposition with the preceding pick of filling b and accordingly this takes place and the row of loops, in this case the row of uncut loops, is shifted into substantial alignment with the preceding row of cut loops so that the appearance is given of a composite row made up of cut and uncut loops. 35 40 As this takes place in each repeat, it will be seen that a rich, full face of pile may readily be formed over the entire fabric consisting of composite rows of cut and uncut loops arranged according to the desired pattern.

45 The same principle is employed in the construction shown in Figs. 6 to 8, inclusive, where a smaller section of fabric is illustrated. In this case there are similar repeats 28, 29, and 30 of four picks of filling d, e, f, and g, with the ground warp ends 31 extending over, under, and over the successive repeats of four picks of filling, while the ground warp ends 32 alternating therewith extend under, over, and under the said repeats, thus with all the ground warp ends crossing only between the successive repeats. In this construction the knife pile wires 33 are inserted simultaneously with the picks of filling d, while the plain pile wires 34 are inserted simultaneously with the picks of filling f. The pile warp ends 35, 36, 37 in this case pass alternately over the picks of filling d, under e, over f, under g, and, as in the previous case, are brought under the control of the shed-forming mechanism also over one of the pile wires as required by the pattern. Two ground warp ends are interwoven for each pile warp end because with this type of weave unless this is done, it is found in practice that the pile warp end is apt to roll around the ground warp end at intervals, causing imperfections in the weave. Here again it will be observed that the pick of filling e, that is, the second pick in each repeat, is a free pick, that is, no loop of either row is formed around this pick and there is no crossing of the ground warp ends between 50 55 60 65 70 75 80 85 90 95 100 105 110 115 120 125 130 135 140 145 150 155 160 165 170 175 180 185 190 195 200 205 210 215 220 225 230 235 240 245 250 255 260 265 this pick and the preceding pick of filling *d*. Consequently again when the fabric is beaten up and the pile wires withdrawn, this free pick of filling *e* shifts into juxtaposition with the preceding pick *d*, bringing the successive rows of pile loops into the desired substantial alignment. Also again the pile warp ends are so interwoven with the picks of filling that the filling end extending from each leg of any cut loop passes under, over, and under picks of filling so as to be anchored in the ground and render the pile fast. So also each pile warp end may form a loop in each repeat enabling a rich, full face of pile to be secured.

A third construction in which the invention 15 may be embodied is shown in Figs. 9 to 11, inclusive. In this case the knife pile wires *38* and the plain pile wires *39* are inserted simultaneously with a pick of filling. The pile warp ends *40*, *41*, and *42* pass successively over, under, over and 20 under the picks of filling and are raised over the desired pile wires in the same manner as in the previous construction. Here also, for the reasons already set forth, two ground warp ends are employed for each pile warp end. In this case the 25 ground warp ends do not all cross between the repeats *43*, *44*, *45* of four picks of filling *m*, *n*, *o*, *p*, but the ground warp ends are so interwoven as still to leave the second pick *n* of each repeat a free pick, that is, one in which no loops of 30 either row pass over this pick of filling and one in which there is no crossing of the ground warp ends *46* and *47* between it and the preceding pick *m*. Consequently this free pick *m* in this case lies under all of the ground warp ends and is only 35 restrained by the pile warp ends under light tension so that when the fabric is beaten up and the pile wire withdrawn, it readily shifts into juxtaposition with the preceding pick *m* and again thus brings the two rows of loops into the desired 40 substantial alignment. This construction is secured in this case by causing the ground warp ends *46* to pass under the picks of filling *m* and over *n*, *o* and *p*, while the ground warp ends *47* pass over the picks of filling *m* and *n*, under *o* and over *p*.

Thus in all of these constructions the same principle of the free pick of filling in each repeat of four picks of filling is employed and the same results are secured.

Having thus described the invention, what is claimed as new, and desired to be secured by Letters Patent, is:

1. The method of making a warp pile fabric comprising ground warp ends, picks of filling and pile warp ends on a pile wire loom which consists in inserting a pile wire for each two picks of filling, interweaving the ground warp ends to form a repeat of four picks of filling and two wires and interweaving the pile warp ends with the filling and the wires to leave in each repeat a pick of filling between and free from the two rows of pile loops formed over the two wires and with no crossing of the ground warp ends between the said free pick and the previous pick of filling to enable the said free pick of filling, when the fabric is beaten up and the wires withdrawn, to shift into juxtaposition to the previous pick of filling and bring the rows of pile loops formed by the two wires into substantial alignment.

2. The method of making a warp pile fabric comprising ground warp ends, picks of filling and pile warp ends on a pile wire loom which consists in inserting a pile wire for each two picks of filling, interweaving the ground warp ends to form a repeat of a pile wire and two picks of

filling followed by a pile wire and two picks of filling with knife and plain wires alternating and interweaving the pile warp ends with the filling and the wires to leave in each repeat a pick of filling between and free from the two rows of pile loops formed over the two wires and with no crossing of the ground warp ends between the said free pick and the previous pick of filling to enable the said free pick of filling, when the fabric is beaten up and the wires withdrawn, to shift into juxtaposition with the previous pick of filling and bring the row of uncut pile loops formed by the plain pile wire into substantial alignment with the row of cut pile loops formed by the knife pile wire.

3. The method of making a warp pile fabric comprising ground warp ends, picks of filling and pile warp ends on a pile wire loom as defined in claim 2, in which each pile warp end in each repeat is passed over one pile wire thus to form 10 an uncut or a cut loop in each repeat of four picks of filling.

4. The method of making a warp pile fabric comprising ground warp ends, picks of filling and pile warp ends on a pile wire loom which consists in inserting a pile wire for each two picks of filling with knife and plain wires alternating, crossing all the ground warp ends after each repeat of one of said pile wires and two picks of filling followed by the other of said pile wires and two picks of filling and interweaving the pile warp ends with the filling and the wires to leave in each repeat a pick of filling between and free from the two rows of pile loops formed over the two wires to enable the said free pick of filling, when the fabric is beaten up and the wires withdrawn, to shift into juxtaposition with the previous pick of filling and bring the row of uncut pile loops formed by the plain pile wire into substantial alignment with the row of cut pile loops 30 formed by the knife pile wire.

5. The method of making a warp pile fabric comprising ground warp ends, picks of filling and pile warp ends on a pile wire loom as defined in claim 4, in which each pile warp end in each repeat is passed over one pile wire thus to form 45 an uncut or a cut loop in each repeat of four picks of filling.

6. The method of making a warp pile fabric comprising ground warp ends, picks of filling and pile warp ends on a pile wire loom which consists in inserting a pick of filling, inserting a knife pile wire, inserting a second pick of filling, inserting a third pick of filling, inserting a plain pile wire, inserting a fourth pick of filling and then repeating, crossing all the ground warp ends after each such repeat, interweaving the pile warp ends with the filling and the wires to leave the third pick of filling in each repeat between and free from the two rows of pile loops formed over the two wires to enable the said free pick of filling, when the fabric is beaten up and the wire withdrawn, to shift into juxtaposition to the previous pick of filling and bring the row of uncut pile loops into substantial alignment with the row of cut pile loops.

7. The method of making a warp pile fabric comprising ground warp ends, picks of filling and pile warp ends on a pile wire loom as defined in claim 6, in which each pile warp end in each repeat is passed over one pile wire thus to form 70 an uncut or a cut loop in each repeat of four picks of filling.

8. The method of making a warp pile fabric comprising ground warp ends, picks of filling and 75

pile warp ends on a pile wire loom which consists in inserting simultaneously a pick of filling and a pile wire, inserting a second pick of filling, in inserting simultaneously a third pick of filling and a pile wire, inserting a fourth pick of filling and then repeating with knife and plain pile wires alternating, crossing all the ground warp ends after each such repeat, interweaving the pile warp ends with the filling and the wires with the 10 said pile warp ends in each repeat passing successively over, under, over, and under the picks of filling to leave the second pick of filling in each repeat between and free from the two rows of pile loops formed over the two wires to enable 15 the said free pick of filling, when the fabric is beaten up and the wires withdrawn, to shift into juxtaposition to the previous pick of filling and bring the row of pile loops formed by the second pile wire into substantial alignment with the 20 row of pile loops formed by the first pile wire in each repeat.

9. The method of making a warp pile fabric comprising ground warp ends, picks of filling and pile warp ends on a pile wire loom which consists in inserting simultaneously a pick of filling and a knife pile wire, inserting a second pick of filling, in inserting simultaneously a third pick of filling and a plain pile wire, inserting a fourth pick of filling and then repeating, crossing all 25 the ground warp ends after each such repeat, interweaving the pile warp ends with the filling and the wires with the said pile warp ends in each repeat passing successively over, under, over, and under the picks of filling to leave the second 30 pick of filling in each repeat between and free from the two rows of pile loops formed over the two wires to enable the said free pick of filling, when the fabric is beaten up and the wires withdrawn, to shift into juxtaposition to the previous 35 pick of filling and bring the row of uncut pile loops into substantial alignment with the row of cut pile loops.

10. The method of making a warp pile fabric comprising ground warp ends, picks of filling and pile warp ends on a pile wire loom which consists in inserting simultaneously a pick of filling and a pile wire, inserting a second pick of filling, in inserting simultaneously a third pick of filling and a pile wire, inserting a fourth pick of filling and then repeating with knife and plain pile wires 45 alternating, interweaving the ground warp ends in each repeat with one set passing successively over the first and second, under the third, and over the fourth pick of filling, and the other set 50 passing successively under the first and over the second, third and fourth picks of filling to leave the second pick of filling in each repeat between and free from the two rows of pile loops formed over the two wires to enable the said free pick 55 of filling, when the fabric is beaten up and the wires withdrawn, to shift into juxtaposition to the previous pick of filling and bring the row of pile loops formed by the second pile wire into substantial alignment with the row of pile loops formed by the first pile wire in each repeat.

11. The method of making a warp pile fabric comprising ground warp ends, picks of filling and pile warp ends on a pile wire loom which consists in inserting simultaneously a pick of filling and a knife pile wire, inserting a second pick of filling, in inserting simultaneously a third pick of filling and a plain pile wire, inserting a fourth pick of filling and then repeating, interweaving the ground warp ends in each repeat with one set 65 passing successively over the first and second, 70 and under the third and over the fourth pick of filling to leave the second pick of filling in each repeat between and free from the two rows of pile loops formed over the two wires to enable the said free pick of filling, when the fabric is beaten up and the wires withdrawn, to shift into juxtaposition to the previous pick of filling and bring the row of pile loops formed by the second pile wire into substantial alignment with the row of pile loops formed by the first pile wire in each repeat.

under the third and over the fourth pick of filling, and the other set passing successively under the first and over the second, third and fourth picks of filling to leave the second pick of filling in each repeat between and free from the two rows of pile loops formed over the two wires to enable the said free pick of filling, when the fabric is beaten up and the wires withdrawn, to shift into juxtaposition to the previous pick of filling and bring the row of uncut pile loops into substantial alignment with the row of cut pile loops.

12. A warp pile fabric consisting of pile warp ends, ground warp ends and picks of filling with the ground warp ends and the picks of filling interwoven to form a repeat of four picks of filling, with the pile warp ends and the picks of filling interwoven to form parallel rows of loops in each repeat with a pick of filling in each repeat lying between and free from the two rows of pile loops and in juxtaposition to an adjacent pick of filling, with no crossing of the ground warp ends between the said free pick and the said adjacent pick of filling and with the rows of pile loops in each repeat standing in substantial alignment and producing the effect of a single composite row.

13. A warp pile fabric having the construction defined in claim 12, in which one of the rows of loops in each repeat is a row of cut loops and the other row a row of uncut loops so that as the two rows stand in substantial alignment, the effect produced is that of a single row made up partially of cut and partially of uncut loops.

14. A warp pile fabric having the construction defined in claim 12, in which each pile warp end in each repeat is interwoven to form either a cut or an uncut loop and in which one of the rows in each repeat is thus formed of cut loops and the other of uncut loops so that as the two rows stand in substantial alignment, the effect produced is that of a single row made up partially of cut and partially of uncut loops.

15. A warp pile fabric consisting of pile warp ends, ground warp ends and picks of filling with all the ground warp ends crossed between each repeat of four picks of filling, with the pile warp ends and the picks of filling interwoven to form a row of cut loops and a row of uncut loops in each of said repeats with a pick of filling in each repeat lying between and free from the two rows of pile loops and in juxtaposition to an adjacent pick of filling and with the rows of cut and uncut loops in each repeat standing in substantial alignment giving the effect of a composite row of cut and uncut loops.

16. A warp pile fabric having the construction defined in claim 15, in which each pile warp end in each repeat forms either a cut or an uncut loop in the respective rows.

17. A warp pile fabric having the construction defined in claim 12, in which the said free pick of filling in each repeat lies under all the ground warp ends.

18. A warp pile fabric having the construction defined in claim 12, in which the said free pick of filling in each repeat lies under all the ground warp ends and in which each pile warp end passes alternately over and under successive picks and in each case under the said free pick.

19. A warp pile fabric having the construction defined in claim 12, in which each pile warp end passes alternately over and under successive picks and in each case under the said free pick.

20. A warp pile fabric consisting of pile warp ends, ground warp ends, and picks of filling with

all the ground warp ends crossed between each repeat of four picks of filling, with the pile warp ends and the picks of filling interwoven to form a row of cut loops and a row of uncut loops in each of said repeats and with each pile warp in each repeat forming either a cut or an uncut loop in the respective rows, with a pick of filling in each repeat lying between and free from the two rows of pile loops and in juxtaposition to an adjacent

pick of filling, with the rows of cut and uncut loops in each repeat standing in substantial alignment giving the effect of a composite row of cut and uncut loops, and with the warp pile end extending from each leg of each cut loop extending under, over, and under separate picks of filling 5 and thus anchored in the ground of the fabric:

GEORGE A. MORGAN.
